Primary Examiner—Joel Sincavage*Attorney, Agent, or Firm*—Poms, Smith, Lande & Rose**[57]****CLAIM**

The ornamental design for a remote control for a bed, as shown and described.

DESCRIPTION

FIG. 1 is a perspective view of a remote control for a bed, showing my new design in its closed state;

FIG. 2 is a front plan view of the remote control;

FIG. 3 is a left side elevational view of the remote control;

FIG. 4 is a bottom side elevational view of the remote control;

FIG. 5 is a top side elevational view of the remote control;

FIG. 6 is back plan view of the remote control;

FIG. 7 is a right side elevational view of the remote control;

and,
FIG. 8 is another perspective view of the remote control for a bed, showing my new design in its open state.
